D. 282,197 1/1986 Hu D23/241

FIG. 1 is a top front perspective view of a faucet body
showing my new design;

FIG. 2 is a front elevational view thereof;

FIG. 3 is a rear elevational view thereof;

FIG. 4 is a right side elevational view thereof, the left
side being a mirror image of the right side; and,

FIG. 5 is a top plan view thereof.

The broken line representation of handles in FIG. 1 is
for purposes of illustration only and forms no part of the
claimed design.
